FIG. 1 is a front elevational view of a light standard or similar article showing my new design.

FIG. 2 is a greatly enlarged cross-sectional view taken on line 2—2 of FIG. 1.

FIG. 3 is a greatly enlarged cross-sectional view taken on line 3—3 of FIG. 1.

FIG. 4 is a top plan view thereof.

FIG. 5 is a front elevational view of a second embodiment of my design.

FIG. 6 is a top plan view thereof.

FIG. 7 is a greatly enlarged cross-sectional view taken on line 7—7 of FIG. 5.

FIGS. 8 through 15 are enlarged front elevational views of further embodiments of my design.

FIG. 16 is a greatly enlarged cross-sectional view taken on line 16—16 of FIG. 15.

FIG. 17 is a greatly enlarged cross-sectional view taken on line 17—17 of FIG. 15.

FIGS. 18 and 19 are greatly enlarged cross-sectional views of a further embodiment of my design taken on planes corresponding to the planes of lines 16—16 and 17—17 respectively on FIG. 15, it being understood that the embodiment differs from FIG. 15 only in cross-section.

FIGS. 20 and 21 are greatly enlarged cross-sectional views of a further embodiment of my design taken on planes corresponding to the planes of lines 16—16 and 17—17 on FIG. 15, it being understood that the embodiment differs from FIG. 15 only in cross-section.

FIG. 22 is an enlarged front elevational view of a further embodiment of my design.

FIG. 23 is a front elevational view of a further embodiment of my design.

FIG. 24 is a top plan view thereof.

FIG. 25 is a greatly enlarged cross-sectional view taken on line 25—25 of FIG. 23.

FIG. 26 is a greatly enlarged cross-sectional view taken on line 26—26 of FIG. 23.

The standard in FIGS. 5, 8 through 15 and 22 is fragmentarily shown for convenience of illustration, it being understood that in overall appearance the embodiments are similar to the complete views in FIGS. 1 and 23. The lamps are shown in broken lines for illustrative purposes only.

I claim:

The ornamental design for a light standard or similar article, as shown and described.
